APPARATUS OF COMBUSTION

John S. Peoples, Chicago, Ill., assignor of one-fourth to Sangston Hettler, Chicago, Ill.

Application October 19, 1935, Serial No. 45,730

5 Claims. (Cl. 158—91)

This invention relates to apparatus for combustion and more particularly to apparatus and process of combustion of oil.

One of the objects of the invention is to provide an improved apparatus for the combustion of oil.

A further object of the invention is to provide an oil burner in which forced draft is provided in such a way that practically all of the apparatus is cooled thereby and protected from the effects of the heat.

A further object of the invention is to provide an improved oil burner in which air is first efficiently carbureted and thereafter the fuel and the air are subjected to combustion.

A further object of the invention is to provide an oil burner provided with a reflection surface associated with a combustion zone in such a manner that radiant heat is reflected upon the oil for the more efficient vaporization thereof.

A further object of the invention is to provide an oil burner in which a pool of oil is maintained in an open vessel during an operation and which will come to efficient combustion condition in a minimum of time.

Other objects, advantages and capabilities of the invention will appear from the following description of a preferred embodiment thereof taken in conjunction with the accompanying two sheets of drawings, in which:

Fig. 1 is a longitudinal section through an oil burner embodying my invention; and

Fig. 2 is a sectional detailed view on a considerably larger scale of the fire pot taken on the line 2—2 of Fig. 1, the manner in which the oil is intermixed with the air being illustrated diagrammatically.

Referring to the drawings, and particularly Fig. 1, the oil burner comprises a dish-like vessel 10 which contains the oil being consumed. The vessel 10 comprises an annular ledge 11 which is provided with an upwardly directed bead 12 within which is received the cylindrical wall of an air housing 13. The housing 13 is secured to the vessel 10 by any suitable means, for example, screws.

The upper end of the cylindrical housing 13 is provided with an integral annular wall 14 which is preferably stepped adjacent its inner edge as shown in Figs. 1 and 2. It will be noted that the wall 14 provides a central opening 15 which is substantially smaller than the dish-shaped vessel 10 located below it.

On its inner side the ledge 11 is provided with a bead 16 which surface has a seat for the lower

edge of the cone 17. This cone tapers upward and its upper edge seats against a face 17' provided by one of the step formations of the wall 14. The wall 14 has an annular portion 14' which extends inwardly beyond the cone 17 for a purpose hereinafter described. The cone 17 and the housing 13 constitute between them an annular chamber for air which is supplied through a conduit 18 which may be bolted to the housing 13. This air is supplied by a blower 19, preferably of the squirrel cage type, which is driven by suitable means, for example an electric motor 20. The oil is supplied by the pipe 21 to the vessel 10 from a suitable control of known type illustrated diagrammatically and designated by the reference numeral 22. This control comprises an electrically operated valve together with a float valve which closes automatically when a predetermined maximum level is reached. As a result, when the conventional control such as the usual household thermostat calls for heat, the first valve is opened and oil passes into the dish-like vessel 10 until the appropriate depth is attained. When the thermostatic control closes the electrical valve in the control element 22, the oil in the vessel 10 is completely consumed. The motor 20 is preferably arranged to run continuously, although suitable means may be provided to render it intermittent so as to supply air only when the oil is burning.

It will be understood that the burner is provided with a suitable pilot light which may be of any known or suitable type. I have illustrated the burner as being provided with an oil pilot of the type described and claimed in my co-pending application, Serial No. 38,247, filed August 28, 1935.

The cone 17 tapers in the upward direction to a substantial degree. This cone is provided with perforations which are relatively sparse in the lower portion of the cone and are relatively numerous in the upper portion of the cone. Thus I may provide four rows of perforations 23 at various heights, each of which comprises a relatively small number of openings distributed uniformly around the circumference of the cone.

Adjacent the upper edge of the cone I provide a plurality of rows, for example four, of similar openings 24, very close together, each row comprising many more openings than those rows below. The angle of the cone is sufficiently steep that the air projected from the openings of the lowest row are able to hit the body of oil maintained in the vessel 10 in the manner shown in Fig. 2.

The jets of air entering from the lowest row of openings impinge against the surface of the oil in the vessel 10 at positions short of the center. All these jets of air, after impinging on the surface of the oil, pass over said surface towards the center, wiping the surface of the liquid oil and carrying oil vapors with them. The air and the oil vapors rise upwardly through the cone and are augmented by the air jets introduced by the other openings 23. The amount of air introduced by the openings 23 is sufficient to provide a combustible mixture of air and oil vapor. The oil vapor is not, however, consumed until it receives the large amount of air supplied by the numerous openings 24. The openings 23 of the rows above the lowest, supply jets of air under pressure which are also directed downwardly and some of these jets also wipe the surface of the oil in the vessel 10. The jets of air wiping the surface of the oil materially aid in its evaporation and in the maintenance of the body of oil at a temperature which avoids cracking and the formation of carbon. The upper openings 23 also create turbulence of the mixed air and vapors and render the mixture uniform in preparation for its upward passage through the zone of high aeration constituted by the numerous openings 24 at the upper edge of the cone.

In Fig. 2 I have illustrated diagrammatically the manner in which the jets of air from the lowermost openings 23 impinge against the surface of the oil and move thereover. In this figure I have also shown a zone of rapid combustion around the openings 24. The amount of air admitted by these openings is so large that it tends to create an eddy current in the form of a gyrating annulus within the cone 17. This gyration of the non-explosive gases together with the agitating effect of the jets entering through the openings 23 maintain the non-explosive gases in a very perfect state of uniformity and turbulence and prevent the occurrence of isolated highly oxygenated zones which might occasion cracking and the deposition of carbon.

The large amount of air introduced by the openings 24 creates a zone of fire around the upper edge of the cone and a column of fire projects upwardly through and beyond the central opening 15. It will be noted that combustion within the burner proper is restricted to a relatively small area around and within the upper end of the cone. I have diagrammatically shown in Fig. 2 the manner in which heat from this annulus of flame is effectively reflected by the annular portion 14' of the wall 14 which projects inwardly beyond the inner edge of the cone. The heat radiated downwardly by the annulus of the flame and also the heat reflected downwardly by the annular portion 14' under ordinary conditions is sufficient to maintain the oil in the chamber 10 at a sufficiently high temperature to effect its vaporization, particularly when aided by the forcible surface wiping effected by the jets of air admitted by the lowermost row of openings 23.

The cone 17 can be very easily fabricated from a blank of appropriate shape. This blank may be bent so as to bring its edges into overlapping relation. These edges are then secured together by welding or any other suitable means. The cone 17 may be made of relatively light metal, preferably heat resisting steel. This cone is maintained at a remarkably low temperature owing to the continuous supply of comparatively cold air around the exterior surface of the cone. As a result of this efficient cooling, I have found that

the cone 17 may be made of very thin metal without danger of burning out.

It is to be noted that the characteristic operation of the present burner is based upon the supply of air under substantial pressure to the lowermost row of openings 23. It is this substantial pressure that produces jets strong enough to reach the surface of the oil and impinge thereagainst with sufficient force to materially aid in the carburetion process.

Although the present invention has been described in connection with a specific embodiment of apparatus and the preferred manner of operation of the process of combustion, it must be understood that I do not intend to be limited to the specific details shown except insofar as set forth in the following claims. Having thus described my invention, I declare that what I claim is:

1. An oil burner comprising a vessel for maintaining a body of oil, a perforated cone above said vessel and tapering upwardly therefrom, a reflecting member above the cone and projecting inwardly thereof for a substantial distance in the radial direction, means establishing an annular chamber around said cone, and a blower for supplying air under pressure to said annular chamber to cool the cone, said chamber terminating short of the oil containing vessel to avoid undue cooling thereof the perforations of the cone being arranged to direct air from the blower downwardly into the oil containing vessel.

2. An oil burner comprising a dish-like vessel for maintaining a body of oil, a cone mounted upon and above said vessel and tapering upwardly therefrom, said cone being provided with openings for the admission of air, walls around the cone and in spaced relation thereto, establishing an annular air chamber around the cone and above the vessel, and a blower to supply air to the annular air chamber which passes forcibly through the openings of the cone, said cone and its openings being arranged so that the jets of air admitted by certain of said openings impinge forcibly upon the surface of the oil in said vessel.

3. An oil burner comprising a dish-like vessel for maintaining a body of oil, a cone mounted upon and above said vessel and tapering upwardly therefrom, said cone being provided with openings for the admission of air, walls around the cone and in spaced relation thereto, establishing an annular air chamber around the cone and above the vessel, and a blower for supplying air to the annular air chamber which passes forcibly through the openings of the cone, said cone and its openings being arranged so that the jets of air admitted by certain of said openings impinge forcibly upon the surface of the oil at positions short of the center of said vessel.

4. An oil burner comprising a shallow vessel for maintaining a body of oil, an upwardly tapering cone mounted upon and above said vessel, means at the upper end of said cone defining an issuing throat, means enclosing an air chamber around said cone, a blower for supplying air under pressure thereto, said cone being provided with openings for admitting air jets under pressure, the slope of the cone and the location of the lowermost openings being arranged so that the perpendiculars to the surface of the cone at their locations strike the oil level short of the center of the vessel.

5. An oil burner comprising a lower member including a relatively shallow vessel for containing a body of oil, an upwardly tapering perforated

cone resting thereon, an upper member above said cone connected to said lower member to provide an air chamber around said cone, and a reflecting flange extending inwardly for a substantial distance in the radial direction beyond the upper edge of the cone, said members being provided with seat formations engaging the upper and

lower edges of said cone, said cone having a row of sparsely located openings adjacent its lower edge and rows of sparsely located openings at varying heights on the cone and a plurality of adjacent rows of closely located openings adjacent its upper edge.

JOHN S. PEOPLES.
